HOSE REEL

Filed Dec. 11, 1928

UNITED STATES PATENT OFFICE

ERIC SVADE, OF PORTLAND, OREGON

HOSE REEL

Application filed December 11, 1928. Serial No. 325,216.

My invention relates to hose reels for the handling of garden and lawn hose. The device consists primarily of a frame, a hose reel disposed within the frame, with means associated with the reel and the frame for the selective means for reeling the hose about the hose reel. The hose may be automatically reeled upon the hose reel. Means being provided within the associated elements for raising the hose reel and maintaining the same in locked position relative to the supporting elements after the reeling has been completed.

One of the objects of my invention is to provide simple and efficient means for the automatic reeling of the hose upon the reel by the rolling of the reel in alignment with the hose, the same being accomplished by supporting wheels disposed in alignment with drums disposed upon the hose reel.

A further object of my new and improved device consists in providing a simple locking means for maintaining the hose reel relatively fixed upon the frame, when the hose has been wound upon the reel, or during the winding or unwinding operation.

A further object of my invention consists in providing simple and efficient means to permit the free rotation of the reel relative to the supporting, associated elements to facilitate the withdrawal of the hose from the reel or the winding of the hose upon the reel with the supporting frame disposed in an upright position.

A further object of my invention resides in a relatively cheap construction made of few parts and one that may be used over a relatively long period with a minimum of adjustment and repair.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a perspective, side view of the

assembled device, illustrating the hose reel locked from rotation and in an elevated position within the frame.

Fig. 2 is a fragmentary, sectional, side elevation of the supporting frame illustrating the driving and driven wheels in engagement.

Fig. 3 is a side elevation of the assembled device shown in position for automatically reeling the hose upon or off of the reel.

Fig. 4 is a side elevation of the assembled device, illustrating the device in position to place the hose reel in locked engagement with the supporting device to prevent the rotation of the reel, in either direction, relative to the supporting elements.

Fig. 5 is a fragmentary, side elevation, of the assembled device, illustrating the hose reel in position for manual winding or unwinding of the hose from the reel.

Like reference characters refer to like parts throughout the several views.

I preferably make my device of two side frame members 1 and 2, having a plurality of spreader bars 3, 4 and 5, disposed therebetween for affording rigidity to the side frame members and to act as hand engaging handles for the user of the device. The lowest of the bars acts to prevent the rotation of the reel. Stub shafts 6, are disposed the lower end of the side frames upon which supporting wheels 7, are journaled to act as trunnion wheels for the supporting of the device and to act as driving wheels for rotating the hose reel. The hose reel is primarily composed of rectangular side wall members having relatively equal width of sides, as illustrated at 8, 9, 10 and 11, and having cross bars 12, disposed therebetween for acting as spreaders for the side wall members and to compose the supporting elements for the hose to be wound thereabout. A drum is disposed adjacent the inner surface of the side frame members. The cross bars about which the hose is to be wound should be so spaced that a reel of a larger diameter than that of the wheels 16 is formed so that the hose reel drum formed by the cross bars will be rotated at a greater peripheral speed than that of the wheels. The reason for so doing is to com-

pensate for any uneven alignment that occurs in the hose to be reeled upon the drum. When so made the hose will be completely wound about the drum without passing over any portion of the hose with the device as the hose alignment is traversed in the reeling operation. The central shaft 13 also extends through gusset plates 14, secured to the side frames 1 and 2. Each of the gusset plates has a slot 15 disposed therein into which the shaft 13 extends and is slidably and rotatably disposed therein. Disposed about the shaft 13 and adjacent either end thereof are wheels 16. The wheels 16 are in registerable alignment with the wheels 7. The wheels 16 are fixedly secured to the side wall members of the reel. The slot 15 has a return 17 disposed therein and when the shaft 13 is placed within the return 17, the wheels 16 are out of engagement with the wheels 7, the reel is held against rotation in either direction, but when the shaft 13 is placed within the slot 15, the engagement of the wheels 16 are permitted with the wheels 7 and the total weight of the hose reel and the hose is disposed upon the wheels 16 and the wheels 7. The contacting of the wheel 7 with the supporting medium and the movement of the same across the supporting medium, rotates the wheel 7 and in turn drives the wheel 16 thereby rotating the hose reel. If the hose is to be unwound from the hose reel, the device is transported to the farthest point at which the sprinkler nozzle head 18, is to be used, is released from the locking bracket 19 and the return of the device to the source of supply of the water, unwinds the hose from the reel, so that the water connection may be made. After the sprinkling operation has been completed, the hose may be wound upon the reel by the passing of the hose for at least one turn about the reel and then retracing the hose with the device thereby automatically reeling the hose upon the reel.

The primary purpose in making the side walls of the hose reel of two rectangular members, as illustrated in Fig. 4, is to form a locking notch between the corners of the side wall members 20 and 21, so that the shaft 13 may be made to engage the return slot 17; in so doing the corners 20 and 21 of the side wall members of the reel are made to engage between the spreader bar 5, thereby preventing the rotation of the reel, and at the same time raising the driven wheel 16 free and clear from the driving wheel 7. A supporting bracket 22 is disposed and outwardly extends from the side frames 1 and 2 that acts as a support for the assembled device. The bracket 22 maintains the device in an upright position, as illustrated in Fig. 1. The lower ends 23 of the side frame members 1 and 2 act as supporting members in conjunction with

the bracket 22 to maintain the assembled device in a relatively upright position.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination of a pair of frame members, spreader bars disposed between the frame members and secured thereto, gusset plates secured to the lower ends of the frame members, said plates having hook shaped slots, stub shafts, supporting wheels disposed upon the stub shafts adjacent the lower ends of the frame members, a central shaft rotatably and slidably disposed between the frame members within the slots disposed within the gusset plates, a hose reel secured to the central shaft, said reel having pairs of end members to form V-shaped indentations which act as brakes when the central shaft is placed within the return of the slots and mounting wheels secured to the side of the hose reel in registerable alignment with the supporting wheels disposed adjacent the lower ends of the frame adapted to be placed into and out of engagement with the supporting wheels.

2. In a device of the class described, the combination of frame members mounting supporting wheels adjacent their lower ends, spreader bars disposed between the frame elements and secured thereto, gusset plates having slots therein disposed upon the frame elements, return slots terminating one end of the slots, a hose reel shaft disposed within the slots and adapted for rotation within the slots and for slidable movement within the slots, a hose reel having pairs of end members to form indentations within the peripheral edge of the side walls of the reel mounted on the hose reel shaft and adapted to hold the hose reel against rotation when the hose reel shaft is placed in the return of the slots by coming in contact with a spreader bar of the frame, and wheels mounted upon the hose reel shaft and secured to the side of the hose reel and in registerable alignment with the supporting wheels and adapted to be rotated by contact with the supporting wheels, substantially as shown and described.

ERIC SVADE.
